SHARPENER FOR SLICING MACHINES

John N. Woodington, La Porte, Ind., assignor to
U. S. Slicing Machine Company, La Porte,
Ind., a corporation of Indiana

Application July 23, 1928. Serial No. 294,750

7 Claims. (Cl. 51—248)

This application relates to slicing machines and more particularly to a mounting of a sharpening mechanism for the slicing knife of the machine such as disclosed in my prior application, Serial No. 190,758, filed May 12, 1927.

One object of the invention is to provide an improved mounting for the sharpening stones such that the stones may be easily removed for cleaning purposes.

10 Another object is to provide a mounting for the sharpening stones in which the spindle carrying the stone is inserted into and is resiliently held against the spindle sleeve to rotate as a unit with the sleeve.

15 A further object of the invention is to improve the mechanism for vertically adjusting the grindstone assembly.

Another object of the invention is to provide an improved mounting by which the sharpening 20 assembly is moved as a whole away from the knife.

Other objects will appear from the following description.

The invention is exemplified in the combination and arrangement of parts shown in the accompanying drawings and described in the following specification, and it is more particularly pointed out in the appended claims.

In the drawings:—

25 Fig. 1 is an elevational view showing the grindstone assembly in section;

Fig. 2 is a rear view of the device showing the guide in section and with the housing for the grindstone assembly in section to expose the parts within the housing;

30 Fig. 3 is a section through the grindstone shown at the left in Fig. 1;

Fig. 4 is a detail view showing the arrangement of the spindle in the spindle sleeve.

40 The grindstone assembly is housed within a casing 1 supported by a threaded stud 2 which is threaded into the threaded bore 5 of a sleeve 4. The sleeve 4 is mounted for rotation within an upright tabular supporting element 10 which is 45 slidably mounted upon the bearing housing 61 for the rotary slicing knife 60. The rotary sleeve 4 is provided with a knurled part 6 fastened thereto or integral therewith. A lock nut 7 is threaded onto the stud 2. It will be seen that 50 rotation of the sleeve 4 by the knurled part 6 will result in vertical adjustment of the casing 1.

When the proper adjustment is made, the lock nut 7 is screwed down upon the part 6, and in order to hold the casing 1 stationary with respect 55 to the sleeve 4, a downwardly extending pin 16 is

secured to the underside of the casing and is slidably received in an orifice 20 in a projecting part of the supporting element 10.

A projection 65 is formed on the element 10, and pivoted to the projection is a lever 67 having a detent 68 extending under the knurled head 6 on the sleeve 4. The lower end of the sleeve 4 is provided with a projection 8 which is received in a recess 9 formed in the base portion for the sliding element 10, which base 65 portion is the top of the bearing housing 61 for the slicing knife 60. The lower end of the supporting element 10 is T-shaped, as shown, having laterally extending portions 11 which slide in the groove formed by the upwardly extending portions 70 and the strips 12 which overhang the side edges of the groove and which are detachably held in place by screws 13. A strip 14 having an orifice for receiving the projecting end 8 of the sleeve 4, is interposed between the lower end of the element 10 and the top surface of the housing for the bearing of the slicing knife and is secured in place by the screws 15. The operating mechanism for retracting and projecting the grindstones is essentially the same as that shown in my prior application, above referred to.

Bearing brackets 17 and 18 are secured to the bottom of the casing 1 by means of screws 19, as shown in Fig. 2. The bearing bracket 17, 85 as shown in Fig. 1, has slidably mounted therein a bearing 21 and within the bearing 21 is rotatably mounted a bearing sleeve 22. The bearing sleeve 22 is formed with a flange 34 and the bearing 21 is formed with a recess within 90 which are positioned ball bearings 26, which ball bearings are held in place by the flange 34.

A washer 23 is pinned to one end of the sleeve 22 and co-operates with the flange 34 for holding the ball bearings in place and for preventing 95 longitudinal movement of the sleeve 22 in the bearing 21. The bearing 21 and the bearing bracket 17 are formed with co-operating recesses for receiving a spring 25 which bears at one end against the bracket 17 and which bears at 100 the other end on the projecting portion of the bearing 21, as shown in Fig. 1. This spring normally tends to slide the bearing 21 to the left, as viewed in Fig. 1, and the stone 35 is positioned to contact with the beveled edge of the 105 knife 60 when the stone 35 and the bearing 21 are projected forward. The bearing 21 has fixed thereto a pin 36 which projects upwardly and rides in a slot formed in the bearing bracket 17.

The grindstone 47 is mounted as shown in 110

detail in Fig. 3. A bearing 37 is slidable in the bearing bracket 18 and is normally forced to the right as viewed in Fig. 3 by a spring 25' which bears against one end of the bearing 37 and against a lip 75 on the bearing bracket 18. The bearing sleeve 38 is rotatably mounted within the bearing 37 and is provided with a washer or flange 39 at its rear end bearing against thrust bearings 40 which are positioned 10 in a recess formed in the bearing 37. The bearing 37 has also a pin 41 rigid therewith riding in a slot formed in the bearing bracket 18.

A spindle 42 has secured thereto the grindstone 47 by means of a screw 46 threaded into 15 the end portion 45 of the spindle. The spindle 42 is also provided with a slot 43 which presses against the inner wall of the spindle sleeve 38 so that the spindle and spindle sleeve rotate as a unit.

20 The spindle and spindle sleeve for the grindstone 35 is similarly formed as shown in Fig. 4. The spindle 27 has an end portion 32 fitted into an orifice of the stone 35 and a screw 33 clamps the stone between the head of the screw and a 25 flange 31 formed on the spindle 27. A second flange 30 of the spindle 27 bears against the flanged end portion 34 of the spindle sleeve 22 and the spindle 27 is slotted at 28, providing prong parts 29 which are spread slightly to resiliently engage the inner wall of the sleeve 22. The spindle 42 is therefore provided with resilient means for frictionally connecting the smooth uninterrupted cylindrical inner wall of the sleeve 38 with the spindle to transmit to 35 the grinder the rotary movement of the tubular sleeve 38.

It will be seen that when it is desired to remove either of the stones 35 or 47, it is simply necessary to slide them out of their respective 40 spindle sleeves against the resilient action of their slotted end portions.

A shaft 50 is journaled in brackets 43 and 49 carried by the bearing brackets 17 and 18 and has rigid therewith the handle 58 which is 45 connected to the bracket 49 by a spring 56 tending to rotate the handle and shaft 50 so that cams 51 and 52 hold the stones 35 and 47 away from the knife, as shown in Fig. 1. The cam 51 is attached directly to the shaft 50 while the cam 52 is carried by a sleeve 53 loose on the shaft 50.

The sleeve 53 has two spaced pins 55 projecting therefrom and a pin 54 rigid with the shaft 50 is arranged between the pins 55 so that the sleeve 53 with its attached cam 52 is not moved until after the cam 51 leaves the pin 36 allowing the spring 25' to move the stone 35 in contact with the knife. After the stone 35 has contacted with the beveled edge of the knife, the pin 54 contacts with one of the pins 55 moving the cam 52 to release the pin 41 which allows the spring 25' to move the stone 47 against the other side of the knife to remove the burr formed by the stone 35. Upon releasing the handle 58, the reverse action automatically and quickly takes place, the stone 47 moves away from the knife after the stone 35 so that the burr formed on that part of the knife between the stones may be removed. The sleeve 53 has attached thereto a pin 56 for contacting with a pin 57 on the bracket 49 to limit the range of movement of the sleeve 53. Ratchet mechanism, not shown, may also be provided for holding the stones in contact with the knife, as more fully disclosed 75 in my prior application above referred to.

A recess 71 is positioned rearwardly of the recess 9 and is formed in the strip 14, as shown in Fig. 1. When the supporting element 10 is slid forwardly, as shown in Fig. 1, and the projection 8 extends into the recess 9, it will be impossible to move the grindstone assembly into inoperative position unless the lever 67 is depressed to cause the detent 68 thereon to engage the bottom of the knurled head 6 to raise the sleeve 4. This will permit the stone 47 to clear the knife 60, after which the entire assembly may be slid rearwardly in the guide for the element 10 and the projection 8 positioned in the rear notch 71.

It should be particularly noted that the rod 16 guides the sharpener vertically by confining it to move along upright rectilinear lines. Therefore when the nut 7 is released and the head 6 is turned to rotate the screw-threaded sleeve 4 on the screw-threaded stud 2 the sharpener will be 90 adjusted in elevation relative to the support 61 along rectilinear lines, the rod 16 preventing the sharpener from having any rotary movement relatively to the support 61.

It should also be noted that by grasping the 100 pedestal 10 the operator's thumb may be used at the same time to press the lever 67 toward the pedestal 10 so as to cause the detent 68 to engage the under side of the head 6 and slide the cylindrical sleeve 4 in the cylindrical guideway 105 of the pedestal 10. If the sharpener is in inoperative position the projection or detent 8 will be in the recess 71. Therefore when the operator grasps the pedestal 10 and presses the lever 67 with his thumb the detent 8 will be lifted 110 from the recess 71 and the sharpener lifted to a sufficient elevation that the burr removing grinder 47 will clear the upper edge of the rotary slicing machine knife 60. The upper surface of the plate 14 acts as an abutment for the lower 115 end of the detent 8 to prevent the sharpener from being lowered until after it has been moved rectilinearly along lines parallel to the axis of the knife 60 into the position shown in Fig. 1. That is to say, not until the burr removing 120 grinder has been moved beyond the upper edge of the slicing machine knife can the sharpener be lowered, because not until then is the detent 8 in position to move into the recess in the plate 14 as shown in Figs. 1 and 2. The operator can 125 therefore by grasping the pedestal 10 and the lever 67 move the sharpener into operative position by one straight line movement and in the same way by a reverse straight line movement he can move the sharpener into inoperative position where it will be held by the detent 8 resting in the recess 71. Furthermore, the movements of the sharpener into operative position and into inoperative position may be made very quickly without any risk whatever of the grinders 35 and 130 47 engaging the knife edge, provided the lever 58 is in the position shown in Fig. 1.

While I have shown but one specific embodiment of my invention, I desire it to be understood that I contemplate making such variations 140 that may fall within the scope of the appended claims.

I claim:

1. In a slicing machine, the combination with a supporting base having a recess therein, of a 145 plate in said recess and secured to said base, said plate having a recess therein, a sharpener, a pedestal for said sharpener having means co-operating with said recess for guiding said sharpener, and means coacting with said plate 150

and the recess therein for holding the sharpener in predetermined inoperative positions except when brought into operative relation with the knife in readiness for the sharpening operation.

5. 2. In a slicing machine, the combination with a supporting base having a rectangular guideway therein, of a sharpener for the slicing machine knife, a pedestal for the sharpener, a rectangular plate detachably secured to said supporting base 10 at the bottom of said rectangular recess, an inverted T at that end of said pedestal remote from the sharpener, and detachable plates secured to said supporting base in position to coact with said first-named plate and the guideway in said supporting base to afford sliding guideways for said T to direct the sharpener to and from its position in operative relation to the slicing machine knife.

3. A sharpener for slicing machines comprising a rotary element having a cylindrical opening therein formed with an uninterrupted wall and having an open end, a cylindrical spindle for carrying a grinder adapted to fit into the open end and support the grinder against lateral movement in said opening, resilient prongs on the end of said spindle adapted to engage the cylindrical wall of said opening and prevent accidental longitudinal movement of said spindle in said opening, said resilient prongs being formed by slotting the end of said spindle substantially in the direction of its length and making one transverse dimension of the slotted portion of said spindle greater than the diameter of said opening, and a conically shaped extension on the ends of said prongs to facilitate insertion of the spindle into said opening, said frictional engagement between said prongs and the inner wall of said opening being sufficient to cause rotation of said element and spindle in unison with each other upon rotation of either said element or said spindle without interfering with the removal of said spindle from said opening by an axial pull on said spindle.

4. A sharpener for slicing machines comprising a rotary element having a cylindrical opening therein formed with an uninterrupted wall and having an open end, a cylindrical spindle for carrying a grinder adapted to fit into the

open end and support the grinder against lateral movement in said opening, resilient prongs on the end of said spindle adapted to engage the cylindrical wall of said opening and prevent accidental longitudinal movement of said spindle in said opening, and a conically shaped extension on the ends of said prongs to facilitate insertion of the spindle into said opening, said frictional engagement between said prongs and the inner wall of said opening being sufficient to cause rotation of said element and spindle in unison with each other upon rotation of either said element or said spindle without interfering with the removal of said spindle from said opening by an axial pull on said spindle.

80

85

90

5. In a slicing machine, the combination with a knife sharpener, of a support, a cylindrical guideway in said support, a screw threaded stud secured to said sharpener, a sleeve fitting in and guided by said guideway longitudinally thereof and for rotation therein and having internal screw threads meshing with the threads on said stud, means on said sleeve for turning the same on said stud to move said stud longitudinally of said sleeve to thereby move said grinder to and from said support, and means for guiding the sharpener as it moves to and from said support.

95

6. In a slicing machine, the combination with a supporting base, of a sharpener for the slicing machine knife, a pedestal for said sharpener, and a tongue and groove connection between said sharpener and said pedestal extending in a substantially horizontal direction and at substantially right angles to the cutting plane of said knife.

100

7. In a slicing machine, the combination with a knife sharpener, of a support, a cylindrical guideway in said support, a stud secured to said sharpener, a sleeve fitting in and guided by said guideway having an internal bore for receiving the end of said stud, means for adjusting said stud vertically relative to said sleeve, said stud having vertical movement relative to said support independently of said adjustment, and means for guiding the sharpener as it moves to and from said support and for preventing rotative movement thereof.
